W. F. FESSLER,

SAFETY DEVICE.

APPLICATION FILED APR 3 1912

1,054,101.

Patented Feb. 25, 1913.

UNITED STATES PATENT OFFICE.

WEAVER F. FESSLER, OF GROVE CITY, PENNSYLVANIA.

SAFETY DEVICE.

1,054,101.

Specification of Letters Patent. Patented Feb. 25, 1913.

Application filed April 3, 1912. Serial No. 688,268.

To all whom it may concern:

Be it known that I, WEAVER F. FESSLER, a citizen of the United States, residing at Grove City, county of Mercer, and State of Pennsylvania, have invented certain new and useful Improvements in Safety Devices, of which the following is a specification.

My invention relates to guards for machinery that is, to guards especially adapted for use in conjunction with machines having a number of exposed moving parts such as gear wheels, fly wheels, belts or other rotat- ing or reciprocating elements.

The primary object of my invention is to provide a cover or casing which may be ar- ranged adjacent the exposed moving parts of the machine to prevent persons from accidentally coming in contact with or getting their clothing entangled in said moving parts.

A further object of my invention is to pro- vide a device for the purpose stated of such construction that all portions of the machine shall be visible to the operator and that ac- cess may be readily had to the guarded parts when necessary, in case of accident or to properly attend to the same.

Other objects will appear hereinafter.

With these objects in view my invention consists generally in a support adapted to be secured in position adjacent the machinery to be guarded, and a screen hingedly mounted on said support whereby the screen may be readily swung out of the way when it is desired to have access to the guarded parts.

My invention further consists in forming the hingedly mounted screen of coarse wire screening in order that all parts of the ma- chine may be visible to the operator and at the same time be of sufficient strength to serve its purpose as a guard.

My invention further consists in a hingedly mounted screen as stated in combina- tion with a locking member comprising an arm adapted to be secured to the frame of the machine or adjacent thereto and pro- vided with a hook portion into which a por- tion of the frame of the screen may be sprung and retained.

My invention further consists in various details of construction and arrangement of

parts all as will be fully described herein- after and particularly pointed out in the claims.

My invention will be more readily under- stood by reference to the accompanying drawings forming a part of this specifica- tion and in which—

Figure 1 is a side elevation of a machine 60 guard embodying my invention in its pre- ferred form and illustrating the same in position at the end of a machine. Fig. 2 is a perspective view of the guard and Fig. 3 is a perspective view of the locking mem- 65 ber.

In Fig. 1 of the drawing I have illustrated diagrammatically a machine to which the guard is applied and of which A indicates the frame. The machine *per se* forms no portion of my invention and is illustrated 70 merely to give a clear idea of the arrange- ment and use of the guard, hence detailed description thereof is unnecessary.

The guard proper comprises a frame 1 formed of a rod bent to the proper shape 75 and size and a screen 2 secured thereto. While I have shown in the drawings a screen of particular shape it is to be under- stood that the frame and screen are to be varied in both size and form to suit the par- 80 ticular machine or part to be guarded. I usually prefer to have the screen 2 of con- cave form in order to inclose the moving parts of the machine and have illustrated a device of this form. As illustrated the 85 screen comprises an outer wall 3 and top and side walls 4 and 5 respectively at sub- stantially right angles thereto, the frame 1 being secured to the inner edges 4 and 5, except at the bottom where it is secured di- rectly to the lower edge of the outer wall 3, as at 6 and to the lower edges of the side walls 5, to strengthen said walls where they are liable to be subjected to the most hard usage. In order that the operator may have 90 95 unobstructed view of all parts of the ma- chine I prefer to make the screen 2 of coarse wire mesh as illustrated.

7 indicates a support upon which the screen is mounted. This comprises a bar 100 adapted to be secured to the frame of the machine or adjacent the same and to this

end is provided with off set arms 8 and 9 which are perforated as at 10 to receive the fastening devices by which it is secured in position. The arms 8 and 9 are preferably formed by bending the ends of the bar 7. 11 indicates hinges whereby the guard is hingedly mounted on the support 7.

A locking member is provided comprising a bar 12 adapted to be secured to the 10 frame of the machine or adjacent thereto and provided near one end with a perforation 13 to receive the securing means and at the other end with a U-shaped portion or hook 14 to receive the adjacent portion of 15 the frame 1 when the guard is in closed position. From the construction of the guard it has sufficient resiliency to permit the frame 1 to be sprung into the hook 14. When the operator desires to obtain 20 access to the guarded portions of the machine the frame is readily lifted out of the hook of the locking member and the screen swung upon the hinges 11 until out of the way.

25 The guard above described is of simple construction and efficient for the purpose of preventing persons or clothing from coming accidentally into contact with the moving machine. Furthermore, while completely 30 incasing the moving elements, the operator has full view of all portions of his machine

and may obtain quick access to the same when desired or necessary.

Having described my invention what I claim as new and desire to secure by Letters Patent is:—

1. A guard for machinery comprising a fixed support, a frame hingedly mounted thereon and consisting of a rod bent to the proper shape to substantially surround the 40 machinery to be guarded and a concave screen comprising an outer wall and top and side walls, and having its edges secured to said frame.

2. A guard for machinery comprising a 45 screen consisting of an outer wall, top and side walls adapted to inclose the machinery to be guarded, a frame for said screen comprising a rod bent to shape and secured to the inner edges of said top and side walls 50 and the bottom edges of said side walls and outer wall, said screen being formed of wire mesh, a support, and a hinged connection between said support and said frame, substantially as described.

In testimony whereof I have signed my name to this specification in the presence of two subscribing witnesses.

WEAVER F. FESSLER.
